UNITED STATES PATENT OFFICE.

HARRY AGLOW, OF NEW YORK, N. Y., ASSIGNOR TO ARTCRAFT METAL STAMPING CORPORATION, A CORPORATION OF NEW YORK.

DESIGN FOR A LIGHTING FIXTURE.

Application filed December 23, 1926. Serial No. 20,124. Term of patent 3½ years.

To all whom it may concern:

Be it known that I, HARRY AGLOW, a subject of the King of Great Britain, and a resident of New York, county of Bronx, and State of New York, have invented a new, original, and ornamental Design for a Lighting Fixture, of which the following is a specification, reference being had to the accompanying drawing, forming a part hereof.

The figure in the drawings shows a perspective view of the lighting fixture.

I claim:

The ornamental design for a lighting fixture substantially as shown.

HARRY AGLOW.
